GLASS PRESS

Harold H. Snyder, Mount Lebanon, and Edward H. Bennett, Pittsburgh, Pa., assignors to Forter-Teichmann Company, Pittsburgh, Pa., a corporation of Pennsylvania

Application April 30, 1942, Serial No. 441,111

4 Claims. (Cl. 49—37)

This invention relates to the production of glassware; the object in view is the rapid production of pressed articles of minute accuracy of shape. Practical application of the invention has been made in the production of the reflector element of what is known as the "sealed beam light," used as an automobile headlight. This reflector is of paraboloid shape; it is penetrated in the central region with orifices, temporary and permanent, for air-pump connection, for the passage of the leads of an electric circuit, and for the mounting of a filament within, to constitute the light source; and at its periphery it is adapted to be engaged in hermetically tight union by the periphery of a cover glass or "lens," to complete what is, in effect the bulb of an incandescent lamp. Accuracy of shape is of utmost importance; the efficiency of the headlight is directly dependent on the perfection of the curve of the paraboloid, the symmetry and uniformity of the walls, and the accuracy of the placement of the light source within the reflector.

In the accompanying drawings, Fig. I is a diagrammatic view in side elevation of the essential parts of the apparatus of the invention. In this figure the apparatus of the invention is shown in operative assembly with a glass tank. The fore hearth of the tank is fragmentarily shown in vertical section. Fig. II is a view to larger scale, showing in transverse and vertical section a portion of the apparatus of Fig. I. The plane of section of Fig. II is, in Fig. I, indicated by the line II—II. Fig. III is a fragmentary view in horizontal section, on the plane III—III, Fig. II. Fig. IV is a fragmentary view to yet larger scale, on the plane IV—IV, Fig. III. Fig. V is a view to equal scale with Fig. IV, showing, partly in elevation, partly in section, the closed mold. The plane of section is vertical and longitudinal and is indicated by the broken line V—V, Fig. II. Fig. VI is a view in front elevation of the finished reflector. Fig. VII is a view in section of the completed lamp. Fig. VIII is a view partly in elevation and partly in section of a detail of construction.

The reflector R is pressed in a mold. The mold consists of the usual parts: the relatively stationary, concave or bowl-shaped part 1, the reciprocable, convex plunger 2, and the reciprocable and spring-backed ring 3.

A glass tank delivers from its fore hearth 4 a descending stream of glass of proper viscosity, which, in known manner, and by shears that move substantially in the plane indicated at x—x, Fig. I, cuts the stream into a succession of

parisons G or gobs of accurately determined size. A chute 5 is provided, through which the severed gobs descend one by one and come to place, each in one of a succession of mold parts 1, when these mold parts have come one by one to the position indicated by A, Fig. I. From position A the mold part 1, when it has received its gob, advances to position B, and in position B the mold part 1 is in the position of co-operation with the mold parts 2 and 3. The severing of gobs and the guiding of them to molds are typically illustrated in United States Letters Patent Nos. 1,451,707, Miller; 1,514,526, Honiss; 1,573,273, Plenksharp; and 2,010,334, Stewart.

15 The plunger 2 is rigidly (though adjustably) borne by a cross-head 6, and cross-head 6 is rigidly carried upon the stem 7 of a piston that is reciprocable in the fluid-pressure cylinder 8. Cylinder 8 constitutes the motor element of the press. 20 The adjustability alluded to of the plunger 2 is indicated by the nut 11, engaging from below the cross-head 6 and movable upon a screw-threaded portion 12 of the stem 7.

The ring 3 is mounted upon the cross-head 6 25 by the usual extensible and retractile connection that consists of stems 9 and springs 10, so that the portion of the mold cavity in which the rim of the article is shaped may be completed before the plunger 2 completes its downward, pressing traverse.

The convex face of plunger 2 (which, of course, will ordinarily be formed of steel) is polished and plated with chromium; and the inner and concave surface of the article shaped by pressure beneath it is correspondingly smooth. It is this inner face of the pressed article that is silvered, to afford the reflecting surface of the completed lamp.

40 The glass-feeding and gob-severing apparatus are such as to afford a succession of gobs of uniform and predetermined size, within a very narrow margin of tolerance; and the strength of the springs 10 and the power of the fluid-pressure cylinder 8 are so carefully predetermined and accommodated to one another that the press automatically produces a succession of articles that fill the mold exactly and completely and with no excess of material. The small margin of tolerance in the magnitude of successive gobs is taken care of in minute variation in the length of the stroke of the plunger 2. The plunger descends until, on the complete filling of the mold cavity, the tension of springs 10 becomes effective in opposition to the advance of the plunger. There-

upon the piston in cylinder 8 automatically comes to rest.

The symmetry and uniformity of the walls of the pressed article are, as has been said, matters of utmost importance; and our invention consists in a machine adapted to the production of the articles in quantity, with speed and economy, and yet with no diminution in the perfection of the articles produced. We provide a machine in which a plurality of mold parts 1 are mounted in succession on an endless conveyor, and are by the operation of the conveyor brought one by one to successive positions in which they first receive each a gob of glass and then each co-operates with the plunger 2 in the shaping of the glass. Our invention lies in an organization such that irregularities of structure and wear, inevitably attendant upon the use of such a conveyor, are ineffective to disturb the accuracy of the pressing operation.

The endless conveyor of our invention consists of a succession of blocks 11 with terminal eyes 12, articulated by spindles 13, to form an endless chain. The prolonged spindles carry rollers 14, and by rollers 14 the chain conveyor is mounted upon and carried by a pair of sprocket wheels 15, 16. The axle (16a) of one of these sprocket wheels (16), upon which the wheel is integrally carried, is provided with a pinion 17. Pinion 17 is in mesh with a rack 18, and rack 18 is carried by the stem of a piston reciprocable in a fluid-pressure cylinder 19. The organization is such that the left-to-right traverse of the piston in cylinder 19 effects the advance of the conveyor (in the direction indicated by the arrows *a*, Fig. I) and the range of advance with each such piston traverse is precisely that required to advance a conveyor-borne mold part 1 from gob-receiving position to pressing position. The connections between pinion 17 and the axle of sprocket wheel 16 are such that the return, right-to-left traverse of the piston within cylinder 19 is ineffective to turn the wheel. As an example of one of the several known devices that may be employed to provide such connections, we show in Fig. VIII a ball-ratchet 17a in the body of the pinion.

The conveyor is arranged as shown in Fig. I, extending in upper and lower horizontal reaches that are made continuous in rounded courses at the ends. A strong and rigid frame 20 carries the sprocket wheels; and this rigid frame includes a table-top 21, over which the plates 11 of the conveyor advance in the upper reach of their travel and upon which they firmly rest, as best shown in Fig. V. Throughout the longitudinal extent of the table-top 21 the spindle-borne rollers 14 are confined in channels 28.

The mold parts 1 are spaced at equal intervals, one upon each of the duplicate plates 11; the distance of advance of the conveyor in each recurrence of the step-by-step feed is equal to the centre-to-centre spacing of the plates 11; and that centre-to-centre spacing is sufficient to allow each mold part 1 in turn, after receiving a gob of glass at station A, Fig. I, to come to pressing position B. The interval of rest, during which the piston in cylinder 19 makes its return stroke, is sufficient to allow the plunger 2 to descend in its glass-pressing stroke and to recede again. The glass-feeding and gob-cutting apparatus are adjusted to cause successive gobs G to descend through chute 5 at identically the intervals of time during which successive mold parts 1 come to position A beneath the lower end of the chute.

This is conventional practice, as has already been indicated.

The mold part 1 is so mounted upon the plate 11 that, borne thereby, it still is freely movable, to allow it to come, at the time when the article is pressed within it, precisely to axial alignment with the plunger 2; and means are provided that the advance of the piston in cylinder 8 shall bring the mold part 1 into accurate axial alignment while plunger 2 is still in course of its pressing stroke, and preferably before the plunger shall have entered the mold cavity.

The mold part 1 is stepped into a block 22, and block 22 rests face to face upon plate 11. These meeting surfaces extend horizontally throughout the upper reach of conveyor travel (Fig. V). The plate 11 is centrally perforate. The block 22 is provided with a stem 23 (Fig. V). In the assembly this stem extends through the perforation in plate 11, and the perforation so far exceeds the stem in diameter as to allow lateral play of sufficient amount of the block 22 in sliding support upon plate 11. Upon the lower end of the stem 23 a plate 24 is removably secured; and this plate, engaging at its rim a nether surface of the plate 11, permitting the sliding movement already mentioned, holds the block against separation from the plate. At the four corners of the block 22 rise bosses 25, and through these bosses are formed bores 26. The cross-head 6 of the press is equipped with corresponding downwardly extending stems 27 and these stems at their lower ends are rounded. When in the progress of operation a mold part 1 borne by a plate 11, having received a gob of glass, comes to position B, Fig. I, the piston within cylinder 8 makes its downward and glass-pressing stroke. The descending piston carries integrally the cross-head 6, the plunger 2, and the stems 27. The stems 27 entering the bores 26, by engagement of their rounded lower ends with the rims of the bores, first shift the block 22, so far as may be necessary, to bring the mold part 1 precisely to alignment with the plunger 2, and such accurate alignment will be achieved before the plunger shapes the glass within the mold part 1. Such corrective alignment removes from the pressing operation irregularity consequent upon the structure and wear of such a conveyor as that described; and the accuracy of the alignment results in a pressed article that is perfectly symmetrical, and of uniform wall thickness upon every radial plane.

As the mold parts 1 advance from right to left (Fig. I) from the pressing position B they carry within them, each a pressed and now solidified article. Means are provided for retaining these articles in place in the mold parts until, rounding the left hand end of their course, they come to inverted position, and until in the extent of the lower horizontal reach of conveyor advance they come to the desired point of release. Such means are found in fingers 29 mounted in housings 30. The housings rise from plates 11 upon each side of and in diametrically opposite positions with relation to the block-borne mold part 1. The fingers are longitudinally reciprocable upon the face of the mold part, and they are oppositely advanced from the inactive position, in which the distal ends of the fingers are retracted from the peripheral edge of the mold cavity, to the position shown in Figs. II to IV, in which at diametrically opposite points they overlie the rim of the article R that lies shaped within the mold cavity. A spring-backed bolt 31 with rounded distal end is also arranged in housing 30, and the

spring 32 tends always to drive the bolt 31 outward—that is to say downward, as seen in Fig. IV. Within the housing 30 a shaft 33 is rotatably mounted. This shaft carries two pinions. One of them, the pinion 34, is in mesh with a rack formed upon bolt 31; the other, 35 (here shown to be of segmental extent) is in mesh with a rack formed upon finger 29. As the bolt 31 is advanced finger 29 is retracted; as the bolt is retracted finger 29 is advanced. Normally the bolts 31 are free to respond to the tension of their springs 32 and stand in extended position; and the fingers accordingly stand in retracted position. Rails 36 are provided, that extend marginally along the course of conveyor travel and throughout so much as is desired. Upon these rails the bolts come to bearing and conveyor advance causes them when engaged by the rails to recede within housings 30, and in so doing to effect the extension of the fingers 29. And throughout the extent of rails 36 the fingers 29 continue in extended position. Fig. I shows that the rails 36 extend throughout the rounded end of the course of conveyor travel, and terminate at a point where the inverted mold parts are advancing (from left to right) on the lower horizontal reach of the course. As the bolts pass beyond the ends of the rails 36 their backing springs become effective to drive them outwardly to extended position. Thereupon, through the rack-and-pinion connection described, the fingers 29 are retracted. The article within the mold part 1 then, no longer restrained, falls free from the mold.

A suitable conveyor 37 is provided; the falling article R comes to rest upon it; and upon it is carried (from right to left, Fig. I) to a suitable place of delivery.

In summary, the chain bearing the plurality of mold parts 1 advances step by step, in the direction indicated by arrows a, Fig. I. When a mold part 1 comes to rest in position A it receives a gob of viscous glass. Advancing again, it comes to rest in position B, where it rests solidly supported from beneath upon table-top 21. The pressing plunger then descends. Before it reaches the glass within mold part 1, however, the mold part has by the co-action of stems 27 and bores 26 been trued in its position (to the extent that truing is required), and shifted upon the sustaining plate 11 to accurate axial alignment with the descending plunger. The plunger 2 then completes its downward stroke and the article is shaped. When the plunger recedes the mold part with the article shaped within it advances. As it advances, the retaining fingers are extended above it and continue extended above it until in the course of the return travel of the conveyor on its lower reach these fingers are withdrawn. The freed article then falls to and is received by and carried upon conveyor 37 to the place of delivery.

The reflector, production of which is the immediate object of invention, possesses further refinements of shape. When finished it is perforated at and near its axial centre with perforations: an exactly central perforation, through which the completed lamp may be evacuated. This perforation, when evacuation has been effected, is sealed off. And near the central perforation are others (there may be two of them), through which leads may extend, to carry a filament (commonly a coil) that becomes the light source, and to carry to the supported filament the current under which it becomes incan-

descent. These orifices must be most accurately placed and finished.

The co-operating mold parts 1 and 2, of general paraboloid shape are elaborated in detail. The part 1 is formed near the centre with re-entrant, circular, downwardly tapering recesses 38, within which rise centrally placed upwardly tapering projections 39 of truncated conical form. Plunger 2 carries correspondingly placed downwardly tapering projections 40 of truncated conical shape. Between these, as best shown in Fig. V, the pressed article is provided exteriorly with bosses, and centered in these bosses are aligned recesses sunk in the opposite surfaces—recesses that at their bottoms are separated only by thin septa of glass. These septa may be removed with accuracy, and the surface left by their removal may be left smooth and of accurate conformation and position. The procedure in removing these septa forms the subject-matter of a companion application to this, Serial No. 441,110, filed by me April 30, 1942.

Fig. VII illustrates the finished lamp. Beginning with the reflector after the septa have been removed and the perforations completed, the completion of the lamp is carried out as follows: The inner surface S of the reflector R is silvered. Leads L, L are set in the orifices that stand symmetrically placed adjacent to but spaced from the axis of the paraboloid, and a filament F is added, borne by the leads. This filament becomes the light source, and is, of course, accurately placed at the focus of the paraboloid. The cover glass C is then applied, and the seam of union at the periphery of the two glass parts is made hermetically tight—advantageously by fusion and welding of the glass at the meeting surfaces. When this has been done (the mounting of leads L, L being also hermetically tight), the assembled lamp is connected through the remaining axial orifice with an air pump, and in known sequent procedure the space within the lamp is exhausted of air; and, finally, the orifice sealed off at 41.

Within the terms of the appended claims various modifications are permissible.

We claim as our invention:

1. In apparatus for pressing glass articles that includes a conveyor carrying a succession of molds, a press including a reciprocable plunger, and means for advancing the conveyor step by step in a plane beneath the plunger, the invention herein described which consists in a mold and means for securing the mold to the conveyor in a union permissive of movement of the mold in the plane of conveyor advance, and means borne by the press, movable with the descending plunger, and adapted to engage the mold and to shift it in said plane to co-axial position with the plunger, before the plunger closes with respect to the mold, and means adapted when the plunger opens the mold to move inwardly with respect to the mold for temporarily retaining the molded article therein.

2. In apparatus for pressing glass articles that includes a conveyor carrying a succession of molds in horizontal course, a press including a vertically reciprocable plunger, and means for advancing the conveyor step by step beneath the plunger, the invention herein described which consists in a conveyor member in the form of an orificed block, a mold member formed with a stem of smaller diameter than the orifice in the block and in the assembly resting face-to-face upon

the block with its stem extending within the orifice in the block, and means borne by the press, movable with the descending plunger, and adapted to engage the mold member and to shift the mold member in its face-to-face engagement with the said block.

3. In apparatus for pressing glass articles that includes an endless conveyor carrying a succession of mold parts erect and inverted in successive horizontal reaches, a press including a reciprocable plunger adapted to cooperate with the mold parts in their erect advance, and means for advancing the conveyor step by step, the invention herein described which consists in a mold and means for securing the mold to the conveyor in a union permissive of movement of the mold in the plane of erect mold advance, means borne by the press, movable with the descending plunger, and adapted to engage the mold and by engagement shift the mold in said plane, and a succession of fingers borne by the conveyor and extensible and retractible above

the conveyor-borne mold parts, together with means for effecting the alternate extension and retraction of the finger severally, in response to the advance of the conveyor.

4. In apparatus for pressing glass articles that includes an endless conveyor carrying a succession of mold parts erect and inverted in successive horizontal reaches, a press including a reciprocable plunger adapted to cooperate with the mold parts in their erect advance in the production of said articles, and means for advancing the conveyor step by step, the invention herein described which comprises a succession of members borne by the conveyor and extensible and retractible relatively to the conveyor-borne mold parts, together with means for effecting the alternate extension and retraction of the members temporarily to retain the formed articles in the mold parts during the advance of the conveyor.

HAROLD H. SNYDER.
EDWARD H. BENNETT.
